DRILL SAMPLING DEVICE

Thue Christian Olsen, Woodbridge, N. J., assignor to American Smelting and Refining Company, New York, N. Y., a corporation of New Jersey

Application May 18, 1943, Serial No. 487,449

3 Claims. (Cl. 77—55)

1

This invention relates to sampling devices and more particularly to an attachment for drill sampling machines which is operable to collect the borings and provide suitable protection to the operator against injury caused by flying pieces of metal during the drilling operation. The invention is illustrated and described in connection with the drill sampling of metallic substances for assay purposes, however, the utility of the invention is not limited to this specific application as will be obvious from the following description.

In drill sampling metallurgical products, such as cakes of copper, pig-iron, bullion, ingots and the like, each cake or slab of metal is generally drilled at several points scattered over its surface and the borings taken to provide a composite sample which may be representative of an entire lot or shipment. This drilling and collection of the sample borings, as heretofore practiced, is a rather tedious and time consuming operation and no special provision is made to safeguard the operator against injury from flying metal. Accordingly, it is the principal object of the present invention to provide a drill sampling device which is operable to automatically gather the drillings and deposit them in a receptacle while thoroughly safeguarding the operator against injury resulting from breakage of the tool bit, or the like, while operating the drill.

Another object is to provide a mechanism which may be readily attached to a drill sampling machine and operated to pick up the borings as they are formed and transfer them to a suitable receptacle or container.

A further object is to provide an apparatus of the character described which combines a boring means having a safeguard with a forced draft mechanism for making drillings and concurrently collecting the borings as the drilling proceeds.

Although the novel features which are believed to be characteristic of this invention will be more particularly pointed out in the claims appended hereto, the invention itself, as to its other objects and advantages and manner of operation may be better understood by referring to the following description taken in connection with the accompanying drawings, wherein a preferred embodiment of the invention is given for the purpose of illustration.

In the drawings:

Fig. 1 illustrates diagrammatically in elevation a turret-type radial drill press as used for drill sampling copper cakes, anodes and the like, which is shown equipped with the sample collecting mechanism of the invention; the receptacle

2

means being broken away to show the interior construction and provision for separating the borings from the air stream;

Fig. 2 is a view in elevation of the inverted suction cup and guard means associated with the drill bit and attached to the spindle sleeve of the drilling machine and shown partly broken away, the cup means being illustrated in its lowermost position;

Fig. 3 is a vertical section view taken on the line 3—3 of Fig. 2 and looking in the direction of the arrows;

Fig. 4 is a fragmentary detail view in section taken substantially on the line 4—4 of Fig. 2 and looking in the direction of the arrows, a portion of the guard member being broken away to show the construction more clearly;

Fig. 5 is a detail section view taken on the line 5—5 of Fig. 4 and looking in the direction of the arrows, the movement of air into the cup and about the drill bit being indicated by arrows; and

Fig. 6 is a detail section view, similar to that of Fig. 5, illustrating a modification wherein a blower is utilized to force air through the device and sweep up the sample borings.

Referring to the drawings in detail, particularly Fig. 1, the numeral 10 designates a turret-type radial drilling machine having a horizontally-disposed arm member 11 which is pivotally supported on the column 12. A motor actuated drilling mechanism which is shown diagrammatically at 13 is slidably mounted on the arm member 11 and is adjustable so that the drill bit 14 can be positioned to make vertical borings at one or more places scattered over the surface area of the billet or slab, such as generally indicated by the reference character 15, which is suitably supported on the work table 16. Vertical movement and feed control of the drill bit is provided for in the usual way, for example, by mounting the drill bit spindle sleeve member 17 on a vertically-movable support which is arranged to be raised or lowered by suitable gearing, not shown, operatively connected to the handwheel lever means 18.

The attachment for collecting the drillings, which is the subject matter of the present invention, comprises an inverted cup-shaped means 20 and communicating suction conduit 21. As shown in Figs. 3 and 5, a centrally located aperture 22 in the inverted base portion 23 of the cup member is provided to allow for passage of the drill bit 14. The open end of the cup means 20 is adapted to engage the surface of the billet or slab of metal to be drilled, as shown in Figs.

2, 3 and 5, and form a closure about the lower end of the drill bit confining the borings so that they are readily picked up and conveyed away through the conduit 21 by the stream of air drawn into the cup 20 by the application of suction to pipe 21.

A yieldable contacting member 24, which is preferably made of leather, rubber, sponge rubber, or like flexible material, is secured to the outer side walls of the cup by suitable means, such as by screws 25, to provide a depending portion 26 for yieldingly engaging the surface of the material being drill sampled. The suction conduit 21 communicates with the inner chamber of the suction cup 20 through a throat means 27 formed by flattening the top and bottom portions of the conduit as illustrated in Figs. 2 and 5.

A flap member 28, made of rubber, leather, or like flexible substance, is secured to the underside wall of the conduit in such a manner as to form a restricted air gap 30 between the flap and surface of the material being sampled. Preferably, the flap member 28 extends beyond the end of the under wall portion of the conduit 21, as shown in Fig. 5 so that it will be flexed upwardly by air pressure when suction is applied to the conduit directing a sweeping blast of air about the drill bit as it rotates whereby the borings 32, which are expelled by the bit, are swept away through the conduit 21 into the receptacle 33, the latter being preferably mounted on the arm means 11 of the drill press as illustrated in Fig. 1. This receptacle, however, may be mounted on the movable drill press mechanism 13 or an independently movable support, as desired.

A cylindrical safeguard means 35 is mounted on the triangular base 36 to which the inverted suction cup means 20 is secured. A central aperture 37 in the base 36 registers with the opening 22 in the suction cup base portion 23 and accommodates passage of the drill bit 14. Angle members 38 welded or otherwise fastened to the lower part of the cylindrical guard are provided for securing the guard to the base 36, as illustrated in Figs. 3 and 4. The guard may be made of metal having screen covered openings 39, or, if desired, it may be formed of transparent plastic material or the like, whereby the operation of the drill can be viewed with safety.

The drill bit guard and suction cup mechanism is supported for vertical movement independently of the drill bit, as shown in Figs. 2 and 3, by the rods 40 which are attached at their lower ends to the base 36. Rods 40 are each slidably retained in a guide portion 41 formed on the lower ends of the straps 42 arranged at opposite sides of the guard 35, as illustrated in Figs. 2 and 3. The mechanism is adjustably clamped to the spindle sleeve 17 of the drilling machine by a collar 44 to which the straps 42 are welded or otherwise rigidly attached. A bolt 45 is utilized to secure the collar 44 to the spindle as shown in Fig. 2.

The rods 40 are prevented from sliding out of the guide members 41 by suitable pin means 46 affixed on the ends of the rods as illustrated in Fig. 3. A handle member 47, attached to the base means 36, is provided for assisting the operator in manually raising or lowering the mechanism about the drill bit. For releasably fastening the mechanism in its raised position, a suitable latch means 48, having a finger operable release member 49, is pivotally attached to the inner side of one of the guide members, as shown in Fig. 3. The hook portion 50 is adapted to engage under the base member 36 when the mech-

anism is raised and retain the same in its uppermost position until it is disengaged therefrom by the operator.

To provide a wear-resistant material for limiting the opening 37 through which the drill bit 14 passes, a suitably hardened piece of metal 51, having a central aperture of sufficient size to permit free passage of the drill bit, is mounted on the base member 36, as illustrated in Figs. 3 and 5. By this provision the opening 37 is prevented from becoming enlarged by movement of the rotating bit therethrough while sufficiently limiting the opening so that most of the air flows through the gap 30 located beneath the suction cup as heretofore described.

A flexible hose means 53 is preferably utilized to connect the conduit 21 to the inlet pipe section 54 of the receptacle 33. Suction is applied to the hose and attached conduit 21 by a suitable motor-actuated blower means, which may be of conventional construction, and generally indicated at 55 on Fig. 1. This blower means is preferably arranged on the lid portion 56 of the receptacle 33 and a gas-permeable membrane 57, made of cloth, fine mesh metal screen, or the like, is positioned in the upper part of the receptacle to filter out the borings which are carried to the receptacle by the air stream. These drillings, forming a sample of the material, are deposited in the bottom portion of the receptacle and the air is drawn through the membrane 57, as indicated by the arrows in Fig. 1. After the air has passed from the membrane to the blower, it is discharged outwardly through vent pipe 58. A perforated skirt member 59 attached to the lid 56 suitably supports the membrane 57 away from the lid while the periphery portion of the membrane is held clamped between the lid 56 and rim means 61 of the receptacle, the blower and associated mechanism being removably clamped onto the receptacle by the winged-type hinged bolt construction, such as is illustrated in Fig. 1.

In use a common electrical switch means may be employed for controlling the operation of both the drilling means 14 and suction creating mechanism 55, however independent control means may be used. By utilizing the present invention sample drillings are readily collected, and by providing a number of removable container means for receiving the sample borings, it is possible to obtain drill samples of a number of different kinds of substances easily and quickly. Ordinarily, however, the sample drillings are collected in the receptacle provided and when the desired amount of sample borings have been obtained, the receptacle and interconnecting hose means 53 are removed and cleaned of borings in order to avoid any possible intermixing of samples.

It will be apparent from the foregoing description that the sweeping up of the borings by air flow may be accomplished by blowing air into the cup means 20 instead of sucking the air therein by vacuum-creating means. Such modification is illustrated in Fig. 6, wherein a blower 65, as shown, is suitably fastened to the underside wall of the pipe 21, and arranged to force air into the interior of the cup 20 and outwardly through the pipe 21 to receptacle 33. Further, it will be obvious that the sample particles may be produced by other means functioning in like manner as a drill, for example, by utilizing a gouging, sawing or abrading means which is arranged to operate similarly as the drill illustrated. Such modifications are contemplated as coming within the scope of the present invention.

While certain features of the invention have been disclosed and are pointed out in the annexed claims, it will be understood that various omissions, substitutions and changes may be made by those skilled in the art without departing from the spirit of the invention.

What is claimed is:

1. A sampling device of the character described comprising boring mechanism, means for supporting material to be bored, means comprising a suction cup operatively associated with said boring mechanism, said suction cup means being shaped as an inverted cup and having a yieldable wall portion for engaging the surface of the material to be sample drilled, a tube connected to said suction cup, suction-creating means in communication with said tube for producing a forced draft to enter said cup beneath said yieldable wall to sweep up the drillings formed during the boring operation and transport them through said tube, and receptacle means connected to said tube for collecting the drillings.

2. A drill sampling device for sampling metallurgical products comprising a vertically movable drill bit, means for moving said drill bit into contact with the material which is to be drill sampled, means for rotating said drill bit to make borings in said material, an inverted cup member operatively associated with said drill bit arranged for movement so that its open end engages the outer surface portion of the material being drill sampled forming a closure around said drill bit and confining the drillings, said cup member having a restricted central opening in the inverted bottom portion to provide a passageway for said drill bit and having yieldable outer edge walls for yieldingly contacting the surface of the material during drilling, a conduit connected to said inverted cup closure and communicating with a receptacle, means for causing a current of air to flow through said closure and conduit and about said drill bit during the drilling operation to

sweep up the drillings and convey them to said receptacle, said receptacle and connecting conduit being readily removable for cleaning and recovering sample drillings after each drill sampling operation.

3. In a sampling device of the character described: a vertically reciprocable drill bit rotatable in contact with material from which sample borings are to be taken, an inverted cup-like means movable vertically independent of said drill bit and yieldably engageable during sampling with the surface of the material being sampled to form a closure around the shank of the drill bit and to confine the borings on the surface area enclosed until they are picked up and conveyed away, a conduit communicating with said closure and connected to a receptacle, a passageway beneath said closure for admitting a gaseous stream thereinto, and means for causing a gaseous stream to flow through said passageway into the closure over the surface of the material adjacent the drill bit and through said conduit to the receptacle during the boring operation to sweep up the borings and convey them to said receptacle for collection.
